(57) **CLAIM**

The ornamental design for a footwear article, as shown and described.

DESCRIPTION

FIG. 1 is a front view of a footwear article showing my new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The even-dashed broken lines in the drawings illustrate portions of the footwear article that form no part of the claimed design.

The dash-dot broken lines in the drawings represent stitching that forms no part of the claimed design.

1 Claim, 6 Drawing Sheets
